Primary Examiner — David Muller
Assistant Examiner — Nathan Johnston

(57) **CLAIM**

I claim the ornamental design for a toothbrush holder, as shown and described.

DESCRIPTION

FIG. 1, is a front elevation view of the toothbrush holder showing my new design.

FIG. 2 is a rear elevation view thereof.

FIG. 3 is a side elevation view thereof.

FIG. 4 is a top plan view thereof.

FIG. 5 is a bottom plan view thereof; and,

FIG. 6 is a perspective view thereof.

The broken lines show portions of the design that form no part of the claimed design.

1 Claim, 5 Drawing Sheets
